Primary Examiner — Holly Baynham(74) *Attorney, Agent, or Firm* — Panitch Schwarze Belisario & Nadel LLP(57) **CLAIM**

The ornamental design for a shower rod and end caps, as shown and described.

DESCRIPTION

FIG. 1 is a top perspective view of a shower rod and end caps in accordance with a first preferred embodiment of my design;

FIG. 2 is a top plan view thereof;

FIG. 3 is a bottom plan view thereof;

FIG. 4 is a front elevational view thereof;

FIG. 5 is a rear elevation view thereof;

FIG. 6 is a left side elevational view thereof; and,

FIG. 7 is a right side elevational view thereof.

The broken lines showing back plates are for the purposes of illustrating environment and form no part of the claimed design.
